(Cl. D52—3)

To all whom it may concern:

Be it known that we, Otto W. Timm and Harry R. Greene, both citizens of the United States, the former residing at Van Nuys and the latter residing at Pasadena, in the county of Los Angeles, State of California, have invented a new, original, and ornamental Design for a Vending Machine, of which the following is a specification, reference being had to the accompanying drawing, forming part thereof, in which:

Fig. 1 is a front elevation of a vending machine embodying our new design;

Fig. 2 is a side elevation thereof from one side;

Fig. 3 is a side elevation thereof from the opposite side; and

Fig. 4 is a plan view thereof.

We claim:

The ornamental design for a vending machine, substantially as shown.

OTTO W. TIMM.
HARRY R. GREENE.
